JAMES M. MARK, OF OREGON CITY, OREGON.

BABBITTING-MANDREL.

1,299,981.

Specification of Letters Patent.

Patented Apr. 8, 1919.

Application filed August 25, 1917. Serial No. 188,125.

To all whom it may concern:

Be it known that I, JAMES M. MARK, a citizen of the United States, residing at Oregon City, in the county of Clackamas and State 5 of Oregon, have invented new and useful Improvements in Babbittting-Mandrels, of which the following is a specification.

This invention relates broadly to metal founding, and more especially to molds for 10 lining articles; and the object of the same is to produce a mandrel or male mold member for giving shape to the wear face of a lining of Babbitt metal such as placed in a shaft hanger or a journal box or other box within 15 which a member is adapted to rotate or reciprocate.

The particular purpose of the present invention is to produce a mandrel which may be employed, whether the shell of the box is 20 in one part or in two, which will be or may be mounted on one part or held between two parts, and which will have provision for beveling the corners of the Babbitt lining throughout parts of its length and providing 25 an oil chamber in the upper bearing section throughout part of its length.

Details will be found in the following specification, and are illustrated in the accompanying drawings wherein:

30 Figure 1 is a plan view, Fig. 2 a side view, and Fig. 3 an end elevation of the mandrel with its ribs.

Fig. 4 is a plan view partly broken away, and Fig. 5 an end view showing the device 35 as employed for babbittting a hanger shell.

Fig. 6 is a side view partly broken away showing the mandrel within an ordinary flat journal box.

Fig. 7 is an end elevation showing the 40 mandrel and Babbitt lining within a connecting rod box for pumps and the like.

The mandrel body 1 is a solid steel cylinder having a diameter which is only a fraction larger than that of the shaft intended 45 subsequently for use within the babbitted bearing, and having a length a little greater than the bearing itself. At diametrically opposite sides it has inset into its periphery two longitudinal webs 2, each being prefer- 50 ably rather thicker and stronger where it is embedded within the body than elsewhere, beveled on opposite sides where it protrudes beyond the periphery thereof as at 3, and flat and thin beyond the beveled portion as 55 at 4. The thin portions of these webs are fins designed to fit between the adjacent in-

ner corners of a box such as indicated at B in Fig. 6 or at C in Fig. 7, or said thin fins could overlie the edges of and rest upon a half-box or hanger such as that indicated 60 at H in Fig. 4. These fins therefore space the right hand side of the mandrel body from the contiguous face of the box-section or hanger H a distance which is yet to be filled with the Babbitt metal. Any appropriate means may be employed for holding 65 the body in this position. As seen in Fig. 5 an ordinary clamp 5 is employed, its arm 6 resting beneath the box H, and its screw 7 having a button 8 which bears against the 70 mandrel.

The use of this invention for babbittting a half-bearing or hanger, is well shown in Figs. 4 and 5. After connecting the parts as shown in Fig. 5 and as has already been 75 explained, the mandrel and box or hanger are stood on end as seen in Fig. 4, and the babbitt poured where indicated by the arrow, so that it flows into the space between the mandrel and the hanger and extends 80 around within said space from one thin fin 4 to the opposite thin fin 4, being meanwhile prevented from running out the lower end by any flat surface on which the hanger and mandrel are stood at the time. After 85 the babbitt has set and the parts have cooled, the screw 7 is run back and the clamp removed, and the entire core or body 1 may then be lifted out of place, leaving the hanger H babbitted on its interior in a man- 90 ner which will be clear.

Inset into one side of the body 1, preferably at a point half-way between the two webs 2, is a third web or more specifically a rib 10 whose use is best illustrated in 95 Figs. 6 and 7. When a two-part hanger or box is to be babbitted, the right-hand side of the mandrel shown in Fig. 5 is disposed adjacent the lower half of the box as in Fig. 7, which would be the right hand side 100 of the box C in Fig. 6, but the other side of the mandrel having the rib 10 is disposed adjacent the opposite half of the box, and therefore when the Babbitt metal is poured from that side and permitted to set, a groove 105 11 is formed in the inner face of the babbitt for the purpose of receiving a lubricant as usual. In order to admit the lubricant, this portion of the bearing may have an oil inlet as indicated at 12 in Fig. 7.

Attention is now invited to Figs. 1 and 2. Here it will be seen that the rib 10 and the

bevels 3 of the webs 2 do not extend the full length of the body 1—in fact, they do not extend the full length of the bearing or half-bearing which is to be babbitted, but the 5 fins 4 do. The result is that the soft or fluent Babbitt metal when first poured, flows past both ends of the rib 10 as seen at 13 in Fig. 6 so that eventually both ends of the groove 11 are closed to the loss of oil 10 or other lubricant. Also the soft babbitt may flow past both ends of the bevels 3 as at 15 in Fig. 6; but in order to prevent its escape, the fins 4 are carried the full length of the mandrel as best seen in Figs. 1 and 2. 15 When babbitting a two-part bearing as shown in Fig. 6, the pouring must be done at the two points shown by the arrows.

The beveled portions 3 of the webs 2 will have the effect of beveling the corners of 20 the babbitt in both halves of the bearing. It will be noticed particularly in Fig. 5 that these bevels 3—3 are not alike. The purpose is to bevel the corner of the lower half-bearing to a greater extent than that

of the other half, because ordinarily grease 26 and sediment accumulate to a certain extent therein.

What is claimed as new is:—

The herein described mandrel for babbitting journal boxes and the like, the same 30 comprising a cylindrical core having diametrically opposed longitudinal slots therein, extending the full length thereof and having an additional slot terminating adjacent the ends of the core and disposed intermediate between the first mentioned slots, a rib seated in the last mentioned slot and projecting therebeyond, webs seated in the first mentioned slot and being of a less length than said slots, and an outstanding 35 rib centrally formed on each of the webs and projecting beyond the ends of the webs a distance approximately equaling the length of the core.

In testimony whereof I affix my signature.

JAMES M. MARK.
